OPHTHALMOLOGICAL UNIT FOR PLEOPTIC TREATMENT

Ralph G. Ostensen, Morton Grove, Ill., assignor to
Medical Products Corp., Skokie, Ill., a corpora-
tion of Illinois

Filed Feb. 7, 1966, Ser. No. 945

Term of patent 14 years

(Cl. D57—1)

Fig. 1

Fig. 2

Fig. 3

FIGURE 1 is a perspective view of an ophthalmological unit for pleoptic treatment showing my new design;

FIGURE 2 is a front elevation thereof; and

FIGURE 3 is a side elevation thereof, the opposite side being a mirror image of the side shown.

The undisclosed rear portions are substantially plain.

I claim:

The ornamental design for an ophthalmological unit for pleoptic treatment, as shown and described.
